SADDLE FOR TEXTILE MACHINES

George Repass, Pawtucket, R. I., assignor to H & B
American Machine Company, a corporation of
Maine

Application April 13, 1940, Serial No. 329,502

3 Claims. (Cl. 19—137)

This invention relates to improvements in top roll saddle mechanisms, and particularly to the connection between the back saddle and its supporting member; and has for one of its objects 5 to provide a novel construction by which the point of fulcruming engagement of the back saddle member with its supporting member can be accurately positioned to provide the proper lengths of lever arms of the back saddle to exert 10 the correct weight on the top rolls engaged by the back saddle member required to be used in the different adjusted positions of the top rolls when drafting different lengths of textile fibers.

Another object of the invention is to provide 15 a back saddle having a fulcrum member so arranged that two separate fulcrum points will be alternately available to connect the back saddle with its supporting member at the correct position relative to the same when the back saddle 20 is hung thereon, which fulcrum points will be alternately brought into fulcruming engagement by reversal of the back saddle on its supporting member.

Another object of the invention is to provide 25 a back saddle member of the above character in which each of the two fulcrum points will have substantially a "knife edge" connection with the under side of the saddle-supporting member when the back saddle is positioned in fulcruming 30 engagement with its support.

With these and other objects in view, the invention consists of certain novel features of construction, as will be more fully described, and particularly pointed out in the appended claims.

35 In the accompanying drawings:

Fig. 1 is a transverse sectional view of a part 40 of a textile drafting apparatus employing five pairs of drawing rolls, showing a top roll saddle mechanism having a back saddle constructed in accordance with the present invention and in an operating position;

Fig. 2 is a side elevational view of a portion of 45 the top roll saddle mechanism illustrated in Fig. 1 and showing the back saddle in a reversed position resting on the back top rolls whereby the relative lengths of the lever arms of the back saddle have been changed over those represented in Fig. 1 for effecting the proper pressure distribution on the back top rolls when their settings have been increased to operate on textile 50 fibers of greater length;

Fig. 3 is an enlarged sectional view showing 55 details of construction of the fulcrum member of the back saddle;

Fig. 4 is an end elevational view, partly in sec-

tion, of the fulcrum member shown in Fig. 3 taken substantially on the line 4—4 of Fig. 3;

Fig. 5 is a modified form of fulcrum member embodying the present invention for use in connection with a back saddle; and

Fig. 6 is a vertical sectional view taken on the line 6—6 of Fig. 5.

In the usual drawing mechanisms, constituted by three or more pairs of drawing rollers, various types of saddle or pressure mechanisms have been 10 used hitherto to load by means of weights a plurality of top rolls of the drawing mechanism in which one prior form of top roll saddle mechanism commonly used has consisted of two members, viz., a back or under saddle which rests on 15 the last top roll and also on the next to the last top roll, and an upper or front saddle that rests at one end of a forwardly disposed top roll and has a straight shank extension directed rearwardly which rests on and supports the under saddle 20 member, in which a stirrup hung from the front saddle and sustaining the usual weighted lever transmits the action of the weight to the saddle mechanism to apply pressure in proper proportion 25 to all the top rollers.

In the previous type of top roll saddle mechanism above described, the back saddle is so supported on the straight rearward extension of the front saddle that the weight is applied to the back saddle over a broad area of contact. 30 Consequently, the load or pressure distribution is indeterminate and not capable of control to the limits of precision necessary for obtaining proper weighting of the rolls upon which only the back saddle rests since any adjustment of 35 the point of application of pressure by the stirrup on the front saddle made for the purpose of increasing or diminishing the effective pull of the weight will affect the weight distribution on all the top rolls while any pressure applied to the 40 back saddle is on a bearing portion having a relatively broad area of contact with the straight rearwardly extending shank extension of the front saddle so that there can be secured no slight adjustment of the fulcrum point of the 45 back saddle when the same is reversed in its position on its supporting member; and in order to secure these desirable results I have provided a back saddle having two selectable fulcrum points of line contact which are alternately 50 usable for fulcruming engagement with the under side of its support member, and these fulcrum points consist of a pair of knife edges which form the opposite edges of the top surface of a frusto-pyramid formation so that the weight is applied 55

to the back saddle on a line when the supporting member for the rear saddle is inclined at a slight angle, such as for example, an angle of three degrees from the horizontal; and the distance 5 between these knife edges on the rear is small, such as of the order of one-sixteenth of an inch so that upon reversal of the position of the back saddle on its support the leverage from the second fulcrum points to the point of contact of the back 10 saddle with the back rolls will be of the correct length found in practice to be sufficient to obtain the proper weight distribution; and the following is a more detailed description of the present embodiment of this invention, illustrating the 15 preferred means by which these advantageous results may be accomplished:

With reference to the drawings wherein in Figs. 1 and 2 there is shown for illustrative purposes one of the embodiments which the present invention may take and applied to a five roll drafting system, the arrangement shown therein comprises the front pair of top and bottom rolls 10 and 11, the rear pair of top and bottom rolls 12, 13 and intermediate pairs of top and bottom rolls 14, 15; 16, 17 and 18, 19 respectively, for acting successively on the moving strand of textile sliver or roving as indicated at 20 to attenuate the same in its progressive passage between the rolls. The top rolls 10, 12, 14, 16 and 18 are 25 of the usual short construction, with or without an outer covering of cork or leather, resting upon their respective bottom rolls and suitably journaled at their ends in the cap bar nebs 21 which are adjustable on the cap bar rod 22. The bottom rolls 11, 13, 15, 17 and 19 are of considerable length and suitably journaled in the adjustable bearing blocks 23 on the roll stand 24 in the usual manner in such machines.

The top roll saddle mechanism herein shown 40 comprises that disclosed and claimed in the pending application of Repass and Ahlberg, Serial No. 317,160, filed February 3, 1940, now Patent No. 2,203,419, granted June 4, 1940, in which an adjustable stirrup having fulcruming connection with the front saddle by means of a tooth in interengagement with a selected notch of a toothed formation is positively locked by a detent in all adjusted positions in which separation of the toothed parts cannot be effected without first 45 rendering the detent member ineffective. As illustrated, the top roll saddle mechanism comprises a front saddle 25 which rests on the second and third top rolls 14 and 16, a back saddle 26 which rests on the fourth and last top rolls 18 and 12 respectively, and a stirrup-carrier 27 having a rearwardly extending shank portion 27' and pivoted on the front saddle 25, as at 28, the 50 weighting pressure being derived from any suitable means, such as a weight 30, the effect of which is transmitted to the stirrup-carrier 27 and applied thereby to the front saddle 25 and the back saddle 26 by means of the link 31 and the weight lever 32 which is pivotally sustained on the roller beam 33 by means of the slide 39 and the fulcrum eye 34, and transmits the action of the weight to the top roll saddle through the stirrup 35. The stirrup 35 is pivoted at its deflected 55 lower end to the lever 32, as at 36, and the upper end is deflected and adjustably fulcrumed at its top end on the stirrup-carrier 27 by means of the tooth 37 having interengagement with a selected one of a series of notches of the toothed formation 38. The lever eye 34 is secured to a slide 39 shiftable transversely of the roller beam and having detachable connection therewith substan- 70

tially as disclosed and claimed in the co-pending application of Christopher Walsh for Top roll weighting mechanism, Serial No. 270,969, filed May 1, 1939. A strap 40 held in position by a suitable screw 41 prevents the stirrup 35 from disengaging itself from the selected notch of the saw-toothed formation 38 of the stirrup supporting member if the stirrup 35 is rocked on its fulcrum tooth 37 sufficiently to cause vertical movement of the same. 10

The back saddle 26 is loosely hung on the rearwardly extending shank portion 27' of the stirrup-carrier 27 by means of an upright member 42 integral with the back saddle and formed with a split eye 43, as shown in Figs. 3 to 6, through 15 which extends the shank portion 27' of the stirrup-carrier 27 whereby the rear saddle 26 may be slid therealong into different selected and adjusted positions for varying the weight distribution on the last and the next to the last top 20 rolls of the drawing mechanism when the back saddle 26 rests thereon and straddles one of these rolls, as depicted in Figs. 1 and 2, by means of prongs 44 and 45 which depend from one end portion of the saddle and embrace the neck of the 25 top roll while the trailing portion of the rear saddle has bearing contact with the adjacent rear top roll on a flat surface 46 formed on the under side of the saddle. Thus, when the roll settings of the pairs of rolls 18, 19 and 12, 13 are varied 30 in accordance with the length of cotton staple being drawn, the proper weight distribution on the top rolls 12 and 18 respectively is maintained to compensate for the longer or shorter lengths of the cotton fiber by reversing the position of the rear saddle from that shown in Fig. 1 to the position shown in Fig. 2 in which the prongs 44 and 45 embrace the neck of the next to the last top roll 18, where in the first instance they confine the neck of the last top roll 12. 40

To provide proper weighting pressure on the top rolls 18 and 12 respectively after the roll settings or spacing between the pairs of rolls 18, 19 and 12, 13 are located the correct distance apart for the particular staple of cotton being drafted, I have provided in accordance with this invention, an improved dual fulcrum for the rear saddle in which the point of bearing contact which the back saddle 26 makes with the arm extension 27' when one or the other of the fulcrum edges 50 or 51 of the countersunk portions 52 and 53 at the opposite ends of the eye 43, as shown in Figs. 3 and 4 respectively, are in fulcruming engagement with the arm 27' when the latter is inclined at a slight angle from a horizontal position, such as, for example, three degrees with the plane containing its line of contact with the bottom cylindrical surface 55 of the eye 43. Thus, the edges 50 and 51 may be alternately brought into a fulcruming position by reversal of the rear saddle on the arm extension 27', as indicated by the reversed positions of the rear saddle in Figs. 1 and 2 respectively and hence it is only possible for the extension arm 27' to contact with one fulcrum edge at a time due to the inclined relation of the arm 27' with respect to the back saddle. 55

A modified structure is shown in Figs. 5 and 6 in which the back saddle 26 has the upright member 42 and the split eye 43, as in Figs. 3 and 4, 70 but with a slightly different form of fulcrum arrangement from that shown in those figures in that a plug 60 has one end mounted in a suitable recess in the bottom wall portion of the eye 43, while the other end of the plug extends inwardly 75

of the central opening of the eye and the free end of the plug is provided with a flat end face 61 and two inclined flat side faces 62 and 63 connecting with and located at opposite positions 5 with respect to the face 61. Thus, the respective meeting lines of the face 61 with the faces 62 or 63 will provide spaced knife edges for alternate fulcruming engagement with the inclined arm 27 for obtaining a predetermined and proper 10 amount of weighting action of the back saddle to the top rolls on which it bears.

The foregoing description is directed towards the specific embodiments disclosed herein, which are intended to be illustrative only and not restrictive as it will be obvious that various changes and modifications may be made in the form, construction and arrangement of parts other than those illustrated, without departing from the spirit and scope of the invention, such changes 20 and modifications being restricted only by the scope of the appended claims.

I claim:

1. A back saddle for top rolls of textile spinning machines comprising a body member having 25 a portion constructed to rest in a bearing relationship upon a top roll shaft, and a second portion so arranged as to extend across and rest upon the shaft of an adjacent top roll, and means intermediate the ends of said body upstanding from 30 its top surface and so constructed and arranged as to receive and be loosely mounted on the usual rearward arm extension of a front saddle member to hold the back saddle in a suspended relationship on said arm extension and to permit 35 sliding movement of the back saddle therealong either into different longitudinally adjusted positions or to be wholly removed therefrom, said means having associated therewith a pair of knife edges in spaced relation to each other and arranged for alternate engagement with the undersurface of 40 said arm extension when the latter is in an inclined relation to the horizontal whereby only one of said knife edges at a time will be in fulcruming engagement with the undersurface of 45 said arm extension in one position of the back saddle, the other of said knife edges being brought into fulcruming engagement with the undersurface of the said arm extension by reversal of the back saddle on the arm extension.

50 2. A back saddle comprising an elongated body

member one portion of which carries a pair of depending prongs for straddling opposite sides of a top roll shaft and to hold the remaining portion of the saddle with its underside in a bearing relationship across and resting upon an adjacent 5 top roll shaft, said body member also having intermediate its ends an upright member integral with and extending upwardly from the upper face of the saddle close to substantially its mid-portion, said upright member being formed with a 10 split eye of a size for loosely receiving and sustaining the back saddle on the rearwardly-extending arm of a front saddle, and fulcrum means within said eye at its bottom part presenting two closely spaced parallel knife edges disposed in 15 the same plane for alternate fulcruming engagement with the usual rearwardly disposed arm extension of a front saddle when the arm is in an inclined position to the back saddle.

3. A back saddle for top rolls of textile spinning machines comprising a body member having a portion constructed to rest in a bearing relationship upon a top roll shaft, and a second portion so arranged as to extend across and rest upon the shaft of an adjacent top roll, an upright member intermediate the ends of said body having an opening through which is loosely received the usual rearward arm extension of a front saddle member for sustaining the back saddle in a suspended relationship from the arm extension and to permit sliding movement of the back saddle therealong either into different longitudinally-adjusted positions or to be wholly removed therefrom, and a fulcrum member within 25 and extending upwardly from the bottom surface 30 of said opening in said upright member, said fulcrum member having a flat top surface and oblique front and back surfaces which intersect with said top surface to form a pair of spaced parallel knife edges for alternate engagement 35 with the undersurface of said arm extension whereby only one of said knife edges at a time will be in fulcruming engagement with the undersurface of said arm extension in one position of the back saddle, the other of said knife edges 40 being brought into fulcruming engagement with the undersurface of the said arm extension by reversal of the back saddle on the arm extension.

GEORGE REPASS. 50
